UNITED STATES PATENT OFFICE.

GEORGE TREFS, OF JERSEY CITY, NEW JERSEY.

ADVERTISING DEVICE.

1,150,404.

Specification of Letters Patent.

Patented Aug. 17, 1915.

Application filed July 15, 1913. Serial No. 779,073.

To all whom it may concern:

Be it known that I, GEORGE TREFS, a citizen of the United States, and residing at Jersey City, in the county of Hudson and 5 State of New Jersey, have invented certain new and useful Improvements in Advertising Devices, of which the following is a specification, such as will enable those skilled in the art to which it appertains to make and 10 use the same.

This invention relates to advertising devices or apparatus, and the object thereof is to provide an improved device of this class which is designed for use in connection with 15 tramway or railway cars or other moving vehicles; a further object being to provide an advertising device of this class which will be attractive in appearance and which will command attention wherever it is placed, 20 and with this and other objects in view the invention consists in a device or apparatus of the class specified constructed and operating as hereinafter described and claimed.

My improved advertising device or apparatus involves a suitable frame, support or casing and a card or cards adapted to be mounted therein and provided with a design, picture, or object, or the picture of a person, object or thing, part of which is 25 movable and may be given a vibratory, oscillating or rotary movement by mechanism mounted in the casing and automatically operated by the movement of the vehicle.

The invention is fully disclosed in the following specification of which the accompanying drawings form a part, in which the separate parts of my invention are designated by suitable reference characters in each of the views, and in which;

40 Figure 1 is a perspective view of my improved advertising device and showing the same tilted forwardly, and showing one of the cards mounted thereon and broken away;—Fig. 2 a vertical transverse section on the line 2—2 of Fig. 1;—Fig. 3 a front view showing details of the operative mechanism mounted in the casing;—Fig. 4 a view similar to Fig. 3, but showing a modification;—Fig. 5 a plan view of the construction shown in Fig. 4;—Fig. 6 a view similar to Figs. 3 and 4, but showing another modification;—Fig. 7 a plan view of the construction shown in Fig. 6;—Fig. 8 a partial

section on the line 8—8 of Fig. 5;—Figs. 9, 9^a and 9^b are separate views of the corner 55 portion of a card or cards which I employ, and which are provided with letters and numbers which indicate the mechanism to be employed in the casing in connection with the particular card for giving the movable 60 part of the figure, picture, or the character thereon the desired movement;—Fig. 10 an edge view of the movable part of a card which I employ, and Fig. 11 a view similar to Fig. 1, but showing only a detail. 65

In the practice of my invention, I provide a frame, support or casing *a* which is preferably oblong and rectangular in form and which comprises a front *a*², a back *a*³, a top *a*⁴, a bottom *a*⁵, and ends *a*⁶ and *a*⁷, and the 70 front *a*² is entirely open and the back *a*³ is provided with longitudinal and parallel slots *a*⁸, four of which are shown. The casing may be constructed in any desired manner, however, but the front thereof preferably 75 consists of end and bottom cleats or strips *a*⁹, and I also provide one or more cards *b* which are adapted to be slipped downwardly into position in the front of the casing, as shown in Fig. 2, and which 80 when in position entirely closes said front, and in Fig. 1 a part of one of said cards is shown in position with the left end portion thereof broken away. The back of the casing is also provided with a central vertical 85 division line *a*¹⁰ which divides the said casing into two similar end portions, and the top of each end portion is provided on the back thereof and above the top horizontal slot *a*⁸ with two similar scales *a*¹¹ and *a*¹², 90 said scales preferably beginning adjacent to the outer end portions of the casing and extending inwardly toward the middle thereof, and these scales represent inches and fractions thereof, and the numerals employed begin with three and end with nine, 95 in the construction shown.

Each of the horizontal slots *a*⁸ is provided at one end thereof, preferably the left end, with a circular enlargement *a*¹³, and these 100 horizontal slots are also numbered, 1, 2, 3 and 4, as shown at *a*¹⁴, and beginning with the top horizontal slot, the movable parts or mechanism of the device or apparatus, which are placed in the casing, involve, in the construction shown in Figs. 2 and 3, a block *c* 105

one end of which is provided with a rectangular extension c^2 adapted to be passed out through one of the slots a^8 , a bolt c^3 adapted to be passed inwardly through said block 5 and provided at its inner end with a thumb nut c^4 and a pendulum c^5 provided at its upper end with a horizontal rotary member c^6 mounted in keepers c^7 and c^8 and connected with the block c , and the front end of which 10 is provided with a card attaching device consisting, in the construction shown, of a thimble-shaped head c^9 which passes forwardly in the direction of the card b , and the pendulum c^5 consists of a forwardly curved and 15 downwardly directed arm provided at its lower end with a weight c^{10} .

The card b , shown in position in Fig. 1 is provided at b^2 with a picture or representation of a girl on the front of which is mounted 20 a movable card member b^3 provided centrally of the back thereof with a projecting tapered hub b^4 adapted to be passed through a slot or opening b^5 in the card b and inserted into a thimble-shaped head c^9 of the horizontal rotary member c^6 with which the pendulum c^5 is connected, and to be secured in said head by a pin b^5 , and the front of the rotary member b^3 is formed, printed, painted or stamped to represent a parasol, and with 25 this construction, any movement of the pendulum c^5 will be transmitted to the rotary member b^3 , and said rotary member b^3 will be given an oscillating movement, as will be readily understood, and this device or apparatus is mounted in a car or other vehicle and the movement of said car or other vehicle will be transmitted to the pendulum c^5 , and said pendulum will be given a more or 30 less constant movement, and this movement 35 as will be understood, will be transmitted to the parasol or rotary member b^3 , and this will attract the attention of the occupants of the car or other vehicle.

It will be understood that any desired advertisement may be placed on the card b , or on the rotary member or parasol b^3 , and an attractive advertising device or apparatus for any kind or class of vehicle is produced.

It will be understood that the extension c^2 45 of the block c may be placed in any of the slots a^8 , and adjusted into any desired position longitudinally thereof, and said block may be locked in any desired position of adjustment by means of the thumb nut c^4 .

In Figs. 4, 5 and 8 of the accompanying drawings, I have shown a mechanism designed to give the movable part of the advertising card a complete rotary movement in either direction, and in this form of construction I connect with the block c a U-shaped bracket d in which is mounted a shaft d^2 with which the thimble-shaped head c^9 is connected, and the shaft d^2 is provided with a pinion d^3 , and the rotary part c^6 is mounted in the sides of the bracket d and

provided with a large gear d^4 which meshes with the pinion d^3 , and said shaft is also provided with a widened gear d^5 and with a sleeve d^6 having a raised support d^7 to which is pivoted a pawl d^8 which operates in connection with the elongated gear d^5 , and which may be turned into different positions, as shown in Fig. 8, and by means of this construction, the swinging movement of the pendulum c^5 will give the shaft d^2 a complete 75 rotary movement, and the position of the pawl d^8 will determine the direction of this movement.

It will be understood that the gears d^4 and d^5 are formed integrally or secured together, 80 and that they are rotatable on the part c^6 , and the sleeve d^6 is secured to the part c^6 , and with this construction the rotary member or parasol b^3 would be given a complete 85 rotary movement the direction of which would be determined by the position of the pawl d^8 .

In Figs. 6 and 7 I have shown a mechanical construction by means of which the rotary part or member of the advertising card may be given either an irregular rotary and oscillating movement, or a vertical vibratory movement, and in this form of construction, the shaft d^2 is provided with a spring e which normally holds said shaft in a predetermined position. The rotary part c^6 of the pendulum c^5 is provided with a widened gear d^5 the same as in Fig. 5, and said rotary member is also provided with the support d^7 and pawl d^8 which operates in connection with the gear d^5 , and said gear d^5 is loosely mounted on the part c^6 . In this form of construction a shaft f is mounted parallel with the rotary member, shaft or part c^6 of the pendulum and is provided with a pinion f^2 which meshes with the gear d^5 , and one end of the shaft f is provided with a cam f^3 which is preferably diamond-shaped in form, and mounted on the shaft d^2 inwardly of the thimble-shaped head c^9 thereof is an arm g adapted to turn with the shaft d^2 , and with this construction, the swinging or oscillating movement of the pendulum will give to the shaft d^2 , the head c^9 of said shaft, and the arm g an oscillating movement, the movement of the shaft d^2 and the head c^9 being an oscillating rotary movement, and the movement of the arm g a vertical vibratory or oscillating movement, and in order to provide the vertical vibratory movement referred to, the arm g is provided at one end with a supplemental thimble-shaped head g^2 to which the movable parts are secured the same as to the thimble c^9 .

In Figs. 9, 9^a and 9^b I have shown the corner portion of a card b , or corner portions of cards b , as may be desired, and in Fig. 9 the part of the card shown bears the characters A, 3, R and 5, in the order named, 125 while the card shown in Fig. 9^a bears the 130

characters B, 3, R and 5, in the order named, and the card shown in Fig. 9^b bears the characters C, 3, R and 5 in the order named.

As hereinbefore stated, the block *c* which bears the automatically operated mechanism of the device may be mounted in either of the longitudinal slots *a*⁸ in the back of the casing and may be adjusted to any desired position in either of said slots longitudinally of said casing, and in the use of this device, a party placing the card *b*, shown in Fig. 9, in the casing will note the first character A, which character informs the said party that he is to use the oscillating rotary movement, or that shown in Figs. 2 and 3, and the second character, 3, determines the space in which the above named construction, or movement, is to be placed, and the third and fourth characters R—5 will inform the said party that he should place the said construction, or movement, five inches from the right in the space numbered 3. In other words, the characters A, 3, R—5 aid a party in properly placing or assembling the parts of the device or apparatus.

The card in Fig. 9^a, or the character B thereof informs the said party that the movement or construction shown in Figs. 4 and 5 is to be used, or a complete rotary movement obtained. The card shown in Fig. 9^b or the character C thereof informs the said party that the movement or construction shown in Figs. 6 and 7 is to be used or a rotary oscillating movement obtained, or a vertical vibratory movement, as desired, and it will be understood that the characters 3, R and 5 in Figs. 9^a and 9^b will necessitate no change in the placement of said different mechanical movements, but should it be desired to place either of the movements A, B, C, in either of the other spaces, namely 1, 2 and 4, the second character 3 should be changed, and if the movement should be placed five inches from the left or any other distance right or left, other than that shown on the cards in Figs. 9, 9^a and 9^b, namely R—5, the said characters R and 5 will be correspondingly changed.

Although I have stated in the above paragraph that either one of the movements may be applied to the movable member of the advertising card or element, it must be understood that the advertising card or element may have a picture of any thing or object, or combination of things or objects, a part or parts of which are movable and said part or parts may be given different movements or combination movements, all of which will be made possible by means of the slots in the back of the frame and the numerals placed adjacent thereto and the characters and numerals placed on said advertising cards or elements.

In Fig. 1 I have shown the picture of a

girl with a parasol, as the movable part, and said part may be given, with the construction shown, an oscillating or rotary movement, and in order to give said part a vibratory movement, all that is necessary is to provide the same with an elongated slot through which the connecting element will pass.

It will be understood that my invention is not limited to any particular mechanical construction for accomplishing the results herein set out, nor to any particular number of movable parts on the advertising card or cards with which the frame, support or casing is provided, nor to any particular movements given to said movable parts, all of which features may be changed or modified according to the results required, and various changes in and modifications of the construction herein described may be made, within the scope of the appended claims, without departing from the spirit of my invention or sacrificing its advantages.

Having fully described my invention what I claim as new and desire to secure by Letters Patent is;

1. An advertising device for use in connection with railway cars or other vehicles comprising a frame, the back of which is provided with longitudinal slots, an advertising card detachably mounted in the front of said frame and provided with a movable part, a pendulum support adjustable in one of said slots, a pendulum suspended in connection with said support, and means whereby the movement of said pendulum will be transmitted to the movable part of the advertising card.

2. In an advertising device, a frame, a pendulum support detachably mounted therein and adapted to be moved into different positions, a pendulum suspended from said support, a movable attaching device in operative connection with said pendulum, and a card member detachably connected with said attaching device.

3. In an advertising device, a frame, an advertising card detachably mounted in the front thereof and composed of separate parts one of which is movable, a pendulum support detachably mounted in said frame and adapted to be moved into different positions, a pendulum suspended from said support, and a movable attaching device in operative connection with said pendulum, the movable card member being provided with means whereby it may be detachably connected with said attaching device.

4. In an advertising device, a frame, an advertising card detachably mounted in the front thereof and composed of separate parts one of which is movable, and a pendulum adjustably supported in said frame and adapted to operate said movable part.

5. In an advertising device, a frame, an

advertising card detachably mounted in the front thereof and composed of separate parts one of which is movable, a detachable pendulum support connected with said frame and adapted to be moved into different positions, a pendulum suspended from said support, and means whereby said pendulum will operate said movable part.

In testimony that I claim the foregoing as my invention I have signed my name in presence of the subscribing witnesses this 12th day of July, 1913.

GEORGE TREFS.
